UNITED STATES PATENT OFFICE.

HENRY UNTERMEYER, OF NEW YORK, N. Y.

DESIGN FOR JEWELRY.

SPECIFICATION forming part of Design No. 13,731, dated March 13, 1883.

Application filed December 21, 1882. Term of patent 3½ years.

To all whom it may concern:

Be it known that I, HENRY UNTERMEYER, a citizen of the United States, residing at New York, in the county and State of New York, 5 have invented a Design for Articles of Jewelry, of which the following is a specification.

The invention relates to an improved design for articles of jewelry; and it consists, first, of a light-house upon a field of line-work, the 10 lower part of the field being rectangular and the upper part oval; and, second, of a light-house upon a countersunk field of line-work inclosed by a flat or lapped border, as shown in the accompanying illustration. The line- 15 work on the countersunk field is what is known as "straight-line engine turning," and the light-house is shown in raised work. Other features of an incidental character are

illustrated; but these are not of the essence of the invention. 20

What I claim as new, and desire to secure by Letters Patent, is—

1. A design for jewelry, consisting of a light-house upon a field of line-work, the upper part of the field being oval and the lower 25 part rectangular, substantially as described.

2. A design for jewelry, consisting of a light-house upon a countersunk field of line-work inclosed by a flat or lapped border, as set forth. 30

Witness my hand this 13th day of December, A. D. 1882.

HENRY UNTERMEYER.

Witnesses:

HERMAN GUSTOW,
CHAS. C. GILL.
